UNITED STATES PATENT OFFICE.

JAMES D. REIFSNYDER, OF FLUSHING, NEW YORK, ASSIGNOR TO TULIP CONTAINER CORPORATION, OF COLLEGE POINT, NEW YORK, A CORPORATION OF NEW YORK.

CONTAINER CLOSURE.

Application filed April 5, 1927. Serial No. 181,018.

This invention relates to container closures, and more particularly to the type commonly used in connection with paper receptacles or containers; although it is equally 5 as well adapted for use in connection with various forms of containers. Such closures are usually made of fibrous material, such for example as paper board, etc., and have heretofore been provided with numerous 10 lifting devices for removing the closures or caps from the containers, and for replacing them therein. Various forms of such lifters or "pulls" have been provided in connection with receptacle closures in the form of wire, 15 metal, or flexible sheet material lifts; but none of these have been satisfactory from the standpoint of commercial production, and use over a period of time.

An object of the present invention is to 20 provide a container closure having a lifter, which is adapted for production at a low cost, which is convenient to use and which will withstand repeated use.

Further objects of the invention will more 25 fully appear from the following description taken in connection with the accompanying drawings illustrating by way of example the preferred embodiment of the invention.

The present invention comprises a receptacle closure having a lifter which is hinged thereto and is adapted to normally lie adjacent to and in parallelism with the closure or to be moved to a position extending upwardly therefrom, in which position it may 35 be readily grasped to remove the closure. The hinged construction of the lifter permits the same to be used repeatedly without detriment to the lifter or to the closure of which it forms a part.

40 Referring to the accompanying drawings which illustrate by way of example the preferred embodiment of the invention:

Fig. 1 is a plan view looking from the top,

45 Fig. 2 is a plan view looking from the bottom,

Fig. 3 is a section taken on line 3-3 of Fig. 1, and showing the lifter in its folded position, and

50 Fig. 4 is a side elevation of the closure showing the lifter in its raised position; wherein the closure is shown seated in the mouth of a receptacle which is indicated by broken lines.

55 Referring to the drawings, 1 indicates the body of the closure which is formed of suit-

able fibrous material such for example as paper cardboard, and which is of a suitable thickness to provide for stiffness and also to provide for pivot means for the hinged lifter 2, to be more particularly described 60 following. The lifter 2 is made of wire in the form of a loop having its ends 3 and 4 bent downwardly (Fig. 3) through the disc 1 and then bent rearwardly and upwardly again passing through the disc until the 65 extreme ends of the wire lie closely adjacent to the body of the loop, thereby forming eyes 5 and 6 at the ends 3 and 4 of the loop. As clearly shown in Fig. 3, the ends so formed pass downwardly through the disc 70 1 and at a distance slightly removed pass upwardly and through the disc, thereby enclosing a portion of the disc 1 within each of the eyes 5 and 6. The eyes together with those portions of the disc 1 which they respectively surround form, in effect, a hinged connection between the lifter and the disc.

The lifter is therefore adapted to lie closely adjacent to the top of the disc as shown in Fig. 3, and may readily be raised 80 to the position shown in Fig. 4, in which position it may readily be grasped by the user for removing the closure from the receptacle. This movement of the lifter from its inoperative to its operative position 85 in no way injures the lifter itself or the disc, due to the hinged connection. In addition to this feature, another great advantage of the present invention is that the lifter may be positioned extremely near the marginal edge 90 of the disc, which is very important in closures of this character, due to the fact that they are usually inserted and removed at one edge.

When the closure is used in connection 95 with the type of container indicated in Fig. 4, which is of a general character similar to that shown in my Patent No. 1,608,617, patented November 30, 1926, entitled Machines for assembling containers, the above 100 advantages are of particular importance, since the closure is seated in a recess which is formed as a bead at the mouth of the container and it is much easier to lift the closure from the container when the lift is 105 attached adjacent the margin thereof. Furthermore, this type of container is adapted for holding edibles which may be used only in part at one time, and it is 110 therefore necessary to remove and replace

the container cover a plurality of times. With the usual type of lift which is braided to the disc and which necessitates bending the material of the lift each time it is used, 5 repeated use of the lift is not possible without destroying the same.

Having thus described my invention with particularity with reference to its preferred form, it will be obvious to those skilled in 10 the art, after understanding my invention, that various changes and modifications may be made therein without departing from the spirit and scope of my invention, and I aim in the appended claims to cover such changes 15 and modification as are within the scope of the invention.

What I claim is:

1. A container closure comprising a disc 20 of fibrous material having a metallic lifter provided with an eye at one end which encircles a portion of said disc at a point removed from but closely adjacent to the edge

of the disc, said eye and cooperating disc portion forming a hinged connection between said disc and said lifter wherein the 25 eye encircled portion acts as the hinge pin about which the lifter is adapted to be freely moved pivotally.

2. A container closure comprising a disc 30 of fibrous material having a lifter formed of a loop of wire whose ends are in the form of eyes which encircle respective portions of said disc at a point removed from but closely adjacent the edge of the disc, said encircling eyes and cooperating respective disc portions 35 forming a hinged connection between said disc and said lifter wherein the eye encircled disc portions act as the hinge pins about which the lifter is adapted to be freely moved pivotally.

In testimony whereof I have signed my name to this specification.

JAMES D. REIFSNYDER.
